UNITED STATES PATENT OFFICE.

OSCAR M. BRYAN, OF PERU, INDIANA.

CHALK-LINE DEVICE.

Application filed May 23, 1922. Serial No. 562,951.

To all whom it may concern:

Be it known that I, OSCAR M. BRYAN, a citizen of the United States, residing at Peru, in the county of Miami and State of Indiana, have invented certain new and useful Improvements in Chalk-Line Devices, of which the following is a full, clear, and exact description.

My invention relates to devices for automatically applying chalk to lines used by artisans for striking a straight line and known as chalk lines. An object of my invention is to provide a combined reel and chalk device which will be convenient to operate, which will be positive in its chalking operation, and which will operate so as to cause all of the chalk to be used up and will avoid the formation of grooves and resultant breaking of the chalk. Other general objects are simplicity, inexpensiveness and durability of construction, as well as facility in assembly and renewal of the chalk.

In accordance with my invention the body of chalk is mounted for rotation and has a drive connection, such as suitable gearing or a pulley and belt construction, with the line reel, and the parts are so related that the line contacts with the side face of the chalk as the line is being drawn out and the chalk is being rotated, thereby causing the chalk to be worn off evenly in an axial direction. A spring holds the chalk yieldingly against the line and thus compensates for wear, and preferably the side wall of the casing forms an abutment for the chalk and is so shaped as to provide a clearance between the wall and the face of the chalk from the periphery well toward its center, thus affording easy access for the line to the chalking surface and at the same time avoiding a squeezing of the line against the face of the chalk as the line is pulled out, and also enabling the line to be rewound out of contact with the chalk. Preferably also the opening in the casing serving as a passage for the line is in the form of a slot sufficiently long to accommodate the line in both its chalking and returning positions.

My invention also includes other features of construction and details and arrangements

of parts as will hereinafter more fully appear. I shall now describe the illustrated embodiment of my invention and shall thereafter point out my invention in claims.

Fig. 1 is a side elevation of a complete device embodying my invention. 55

Fig. 2 is a sectional plan of the same, on line 2—2 of Figure 1.

Fig. 3 is an end elevation of the same.

The operating parts are contained within a flat casing 1, generally of oblong shape with one end rounded and provided with a cover 2. The reel 3 for the line 4, is mounted in the rounded end of the casing upon a square shaft 5, the one end of which is rounded and bears in the cover 2, and the other end of which extends through the casing 1 and is secured to the hub of a handle 6 which bears in the side of the casing 1. The handle 6 is shown as jointed so as to enable it to be folded up, the knob entering the hollow shaft 5 as indicated in dotted lines in Figure 2. On the cover end of the shaft 5 is fixed a gear wheel 7, a suitable spacing washer 8 being interposed between the gear 7 and the side of the reel. A friction member, such as a spring 9, may be carried by the cover in position to bear against the side of the reel and steady it and prevent it from turning accidentally. 80

The chalking element is rotatively mounted on another transverse shaft or post 10 near the opposite end of the casing. Surrounding the post 10 is a sleeve 11, the outer surface of which is squared, and the body 85 of chalk 12, preferably of disc shape, has a square axial hole and is disposed upon the sleeve 11. The body of chalk 12 is preferably contained in a cup-shaped metallic holder 13 which is disposed on the cover 90 side of the chalk and fits a little way over the edge leaving substantially all of the rest of the chalk exposed. The chalk and its container are freely slideable longitudinally upon the sleeve 11 and a bow-shaped spring 95 14 having its ends in holes in the cover, bears against the metallic covered face of the chalking element and holds the chalk against the opposite side of the casing. A portion of the side wall of the casing 1 im- 100

mediately surrounding the bearing for the post 10 is concaved, as shown, or otherwise shaped so as to provide an abutment for the chalk near its axis while leaving substantially all of its side face clear from the casing, thus affording ample room for the line 4 to enter between the chalk and wall and engage the side face of the chalk.

A bearing 15 surrounds and fits over the sleeve 11 and bears in the cover 2. A gear wheel 16 is non-rotatably secured upon this bearing 15 and is joined to the gear wheel 7 through an intermediate gear 17 which is pivoted to the cover. It will be noted that the end of the spring member 14 straddles the gear wheel 16.

The end of the casing adjacent the chalking element is provided with a vertical slot 18. For convenience in manufacture, this is shown as extending the whole height of the casing, but for purposes of its function, it need extend no farther than to accommodate the line in the two positions shown in dotted lines in Figure 1, in which 4^a is its position when it is being drawn out and chalked and 4^b is its position when it is being rewound. While, if desired, the slot may be the whole width of the casing, it need be provided only adjacent to the side 30 of the casing which serves as an abutment for the chalk. Preferably a knob 19 is provided on the end of the line to prevent its being drawn entirely within the casing, and the bottom of the casing and the lower corner of the side wall may be cut away, as shown at 20, to provide a seat for this knob. If desired, the top of the casing may have a downwardly turned lip 2^a, as indicated in dotted lines, fitting within the cover to 40 add rigidity to the structure.

It is now apparent that in order to chalk the line, the operator grasps the knob and pulls it out in the position shown at 4^a in contact with the exposed side face of the chalk, the concaved portion of the side wall of the casing surrounding the bearing facilitating the admission of the line to the face of the chalk. As the reel turns it transmits rotation to the chalking element and the side face of the chalk is thus rotated over the line and worn away evenly. After the line has been used, the operator turns the handle 6 to reel in the line, during which operation it falls to the position shown at 4^b. When the device is assembled, it is locked together by means of cotter pins in the ends of the shafts 5 and 10, as shown, the opposite end of the shaft 10 being provided with a head which serves as an opposing abutment.

It is obvious that various modifications may be made in the construction shown in the drawings and above particularly described within the principle and scope of my invention.

I claim:

1. A chalk line device comprising a casing, a line reel and a chalking element rotatively mounted on two parallel transverse bearings in the casing, and the chalking element being slidable on its bearings, the casing having in the end adjacent the chalking element an upright slot adjacent one side providing a passage for the chalk line, a drive connection between the reel and chalking element, and a spring bearing between the other side of the casing and the chalking element and operative to press the chalking element yieldingly against the first mentioned side of the casing. 80

2. A chalk line device comprising a casing, a line reel and a chalking element rotatively mounted on two parallel transverse bearings in the casing, and the chalking element being slidable on its bearings, the casing having in the end adjacent the chalking element an upright slot along one side providing a passage for the chalk line, the said one side of the casing being inwardly concaved opposite the axes of the chalking element so that the said axis coincides with a radius of the concaved portion, a spring bearing between the other side of the casing and the chalking element and operative to press the chalking element yieldingly with its face against the said concaved portion of the casing, and a drive connection between the reel and chalking element. 95

3. A chalk line device comprising a casing open at one end, a reel for the line mounted in said casing and including a transverse shaft having its bearings in the side of the casing, a gear wheel fixedly positioned on the reel shaft, a second transverse shaft bearing in the sides of the casing between the reel and open end of the casing, a squared sleeve surrounding the second transverse shaft, a gear wheel fixedly positioned on the sleeve, a chalking element fitting upon the sleeve and slidably longitudinally thereof, a spring member bearing against the face of the chalking element adjacent the gear wheel and pressing it yieldingly with its other face against the opposite side of the casing, and an intermediate gear pivoted to the casing and meshing with the two said gear wheels. 110

4. A chalk line device comprising a casing open at one end, a reel for the line mounted in said casing and including a transverse shaft having its bearings in opposite sides of the casing, a gear wheel fixedly positioned on the reel shaft, a second transverse shaft bearing in the sides of the casing between the reel and open end of the casing, a squared sleeve surrounding the second transverse shaft, a gear wheel fixedly positioned on the sleeve in alignment with the first-named gear wheel, a chalking element fitting upon the sleeve and slidably 125

130

longitudinally thereof, the side wall of the casing opposite the gear wheel being inwardly concaved for a portion immediately surrounding the shaft for the chalking ele-

ment, a spring member bearing against the face of the chalking element adjacent the gear wheel and pressing it yieldingly

against the said concaved portion of the opposite side wall, and an intermediate gear pivoted to the casing and meshing with the two said gear wheels.

In witness whereof, I hereunto subscribe my signature.

OSCAR M. BRYAN.
